UNITED STATES PATENT OFFICE.

EAMES DONALDSON, OF BUFFALO, NEW YORK, ASSIGNOR TO BRONZO ALUMINA CORPORATION, OF BUFFALO, NEW YORK, A CORPORATION OF NEW YORK.

PHONE ADAPTER FOR RADIO APPARATUS.

Application filed April 30, 1923. Serial No. 635,504.

This invention relates to a phone adapter which is more particularly applicable to the head phones employed in connection with radio receiving apparatus.

Its chief object is to provide an adapter of this character which is so constructed that it is universally applicable to the phonographs of various makes now on the market for the purpose of amplifying the sound, so that all the persons in the room can hear the concerts received by the radio outfit.

Another object of the invention is to provide a phone adapter which is simple and compact in construction, and which may be readily applied to and removed from the sound tubes of phonograph horns without in any way altering their construction or without the use of fastenings.

In the accompanying drawings: Figure 1 is a fragmentary top plan view of the sound tube of one type of phonograph showing my invention applied thereto. Figure 2 is an enlarged longitudinal section on line 2—2, Fig. 1. Figure 3 is a rear face view of the adapter. Figures 4 and 5 are sectional views, similar to Fig. 2, showing the adapter connected with the sound tubes of other types of phonographs.

Similar characters of reference indicate corresponding parts in the several views.

In Figs. 1 and 2, the invention is shown in connection with a phonograph of well known construction, wherein 10 indicates the tone arm and 11 the sound tube pivoted thereto. Removably applied to the end of this sound tube is the phone adapter 12, the same taking the place of the customary reproducer or sound box of the phonograph.

This phone adapter preferably consists of a cap 13 having an internally-threaded socket 14 on one side and a neck or projection 15 at its opposite side provided with a central opening 16 and a counter-bore 17. The counter-bore of said neck is adapted to fit over the sound tube 11, being held thereon by friction. The threaded-socket 14 is adapted to be connected with the diaphragm body or chamber 18 of a head phone, of ordinary construction, from which the customary perforated cap has been removed. In

other words, this phone adapter is substituted for the perforated cover of the head phone, the latter still retaining the diaphragm 19 which is clamped between the adapter-cap 13 and the diaphragm chamber, as shown in Fig. 2.

In using this phone adapter, the cover of one of the head phones of the radio outfit is disconnected and the adapter is screwed in its place, being sure that the latter is screwed on tight and that the diaphragm is properly positioned. Then the reproducer of the phonograph is removed from the sound tube and is replaced with the phone adapter. In the application shown in Figs. 1 and 2, the bore 17 of the cap 13 is of the proper size to fit over the sound tube 11 of certain makes of phonographs.

In Fig. 4, the improvement is shown in connection with a sound tube 20 of another type of phonograph, the internal diameter of this tube being of a size to receive the neck 15 of the adapter cap.

In the embodiment of the invention shown in Fig. 5, the cap 13 is provided with a removable bushing 21 which is fitted within the counter-bore 17 and whose outer end projects beyond the end of the neck 15 and may be provided with an open-ended slot 22. The outer end of this bushing is adapted to fit within a sound tube 23 of another make of phonograph, the bushing-slot 22 being arranged to interlock with the pin 24 of said tube.

From the foregoing it will be understood that I have produced a phone adapter for radio outfits which is universally applicable to the various makes of phonographs now in use, so that the sound waves received are amplified to such a degree that every one in the room can hear them.

The adapter is preferably made of a nickel-aluminum alloy which assures perfect tone qualities, and which, taken in connection with the scientific design of the phonograph, enables musical tones and others to be brought out clearly without distortion or raucous metallic sounds.

I claim as my invention:

1. As an article of manufacture, an adapt-

- er for radio head-phones and the sound tubes of phonographs, comprising a cap separate and distinct from the phone and provided on one side thereof with an internally-threaded socket for receiving the phone and on its opposite side with a neck having a bore, both the neck and the bore constituting means for connecting the adapter with sound tubes of different sizes.
- 10 2. A phone-adapter for use in connection with phonographs having sound tubes, comprising a cap adapted for attachment to the phone, said cap having a bore extending substantially centrally through it and constituting means for connecting said cap to a sound tube of a given size, and a bushing adapted to be removably fitted in said bore for connecting the cap with the sound tubes of different sizes.
- 15 3. A phone-adapter for use in connection with phonographs having sound tubes, comprising a perforated cap adapted for attachment to the phone, the cap having a neck on its outer side having a bore extending through it, both the neck and its bore constituting means for connecting said cap with sound tubes of different sizes, and a bushing adapted to be removably seated in said bore for connecting said cap with sound tubes of a size different from said first-named tubes.
